United States Patent Office

Des. 196,635
Patented Oct. 22, 1963

196,635

TOOTH CLEANER

Anthony Jules Kinsella, 415 Oxford St., London, England

Filed Feb. 15, 1963, Ser. No. 73,584

Term of patent 14 years

(Cl. D9—2)

Fig. 1.

Fig. 2.

Fig. 3.

Fig. 4.

FIG. 1 is a top perspective view of a tooth cleaner showing my new design;

FIG. 2 is a bottom plan view thereof;

FIG. 3 is a side elevational view thereof, and

FIG. 4 is a vertical cross-sectional view taken on lines 4—4 of FIG. 1.

The side not shown is substantially like the side shown.

I claim:

The ornamental design for a tooth cleaner, as shown and described.
